UNITED STATES PATENT OFFICE.

PAUL MOHRMANN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A BOWL FOR INDIRECT LIGHTING.

47,271.

Specification for Design.

Patented Apr. 27, 1915.

Application filed March 6, 1915. Serial No. 12,625. Term of patent 3½ years.

To all whom it may concern:

Be it known that I, PAUL MOHRMANN, a citizen of the United States, residing at Chicago, in the county of Cook and State of Illinois, have invented a new, original, and ornamental Design for a Bowl for Indirect Lighting, of which the following is a specification, reference being had to the accompanying drawing, forming a part thereof.

Figure 1 is a side elevation of a bowl for

indirect lighting, showing my new design. Fig. 2 is a plan view of the same.

I claim:

The ornamental design for a bowl for indirect lighting, as shown.

PAUL MOHRMANN.
